FUSE

Theodore Birkenmaier, St. Louis, Mo., assignor to
W. N. Matthews Corporation, St. Louis, Mo., a
corporation of Missouri

Application February 28, 1936, Serial No. 66,179

33 Claims. (Cl. 200—114)

This invention relates to fuses, and with regard to certain more specific features, to expulsion fuses.

Among the several objects of the invention 5 may be noted the provision of an expulsion fuse in which the fuse link, after blowing, and after being expelled from the fuse tube shall not be electrified (alive) in the condition that it hangs from the fuse unit; the provision of apparatus 10 of this class in which mechanism that accomplishes the de-electrification of the link shall also be useful in effecting a wide separation of the link at the point of fusion; and the provision of a device of the class described which may 15 be easily re-fused. Other objects will be in part obvious and in part pointed out hereinafter.

The invention accordingly comprises the elements and combinations of elements, features of construction, and arrangements of parts which 20 will be exemplified in the structures hereinafter described, and the scope of the application of which will be indicated in the following claims.

In the accompanying drawing, in which is 25 illustrated one of various possible embodiments of the invention,

Fig. 1 is a vertical section taken through a fuse box, showing in elevation therein a fuse tube, the parts being in normal fused and unblown condition;

Fig. 2 is a view similar to Fig. 1 showing a 30 blown condition of the fuse;

Fig. 3 is a vertical section on line 3—3 of Fig. 1;

Fig. 4 is a horizontal section on line 4—4 of 35 Fig. 1; and,

Fig. 5 is a horizontal section taken on line 40 5—5 of Fig. 1.

Similar reference characters indicate corresponding parts throughout the several views of 45 the drawing.

It has been heretofore known to provide a fuse-containing tube having an upper contact and a lower contact spaced from the open bottom of the tube. Between the contacts was connected 45 a fuse link with a fusible element near the upper contact. This link passed through the tubular portion. Upon melting out of the link at said fusible section, the engendered gases, or even auxiliary mechanical means, in some cases, caused 50 the fuse link to be projected from the tube. The circuit was thus broken, but the hanging fuse link was still connected to a contact in the circuit, so that it was either alive or electrified. Thus there was always the danger that a line- 55 man or another might contact it and become

grounded in the circuit, or that the dangling link would contact other conducting objects and so cause trouble. The present invention overcomes this difficulty without the necessity of releasing the link upon blowing.

Referring now more particularly to Fig. 1, there is shown at numeral 1 a fuse box which carries a pivot pin 3 for the hook-shaped portion 5 of a door 7, the latter carrying an eye 9 for manipulating the same to open and closed positions. 10 It is to be understood that in open position, the door may be entirely separated from the box by unhooking the eye from the pivot pin 3, but that in closed position, the pin 3 and eye are inseparable. It is to be understood that both the box 15 1 and door 7 are composed of insulating material, such as porcelain and bakelite, respectively.

At its upper end the door 7 is provided with a support 11 to which is rigidly fastened an upper terminal-engaging element 13 in which is threaded an insulating, hollow, fuse tube 15. The hollow portion of the tube 15 is in alignment with an opening 17 in the terminal-engaging element 13. The terminal-engaging element has threaded therein a cap 19 whereby the upper conducting element 21 of a fuse link may be held in said opening 17.

The terminal-engaging element 13 carries gudgeons 23 which cooperate with notches 24 in spring holding clips 25. The spring clips 25 are 20 fastened to a conducting block 27 to which is fastened a line wire 29. One gudgeon 23 is located on each side of the terminal-engaging element 13 to accommodate respectively one spring clip 25. Between the pair of spring clips 25 is a centrally located clip 31 which, when the gudgeons 23 are seated in the notches 24 of the clip 25, 25 seats on the upper flat surface of the closure cap 19. By this means, when the door 7 is angled to a closed position, the terminal-engaging element 13 is springingly held in the spring clips 25 and 31. The door is thus held shut and contact made for the terminal-engaging element 13.

From the above it will be understood that the element 13 and insulating tube 15 are rigidly held on the door 7. The tube 15 extends downwardly, and, at its lower end is open as indicated at numeral 39. The lower end is adjacent the lower open portion 41 of the box 1. Concentrically, and slidably arranged upon the lower portions of the insulating tube 15 is a second insulating tube 43. The tube 43 is slidable from the position shown in Fig. 1 to that shown in Fig. 2. It has a lower open end 45 adjacent said lower open end 39 of the tube 15.

Rigidly fastened about the lower end of the slideable insulating tube 43 is a contact 47 which carries a clamp 49 for the lower end of the fuse link 51.

Surrounding the slideable insulating tube 43 is a second but movable terminal engaging element 53. This second element 53 instead of being fastened to the tube 43, as is the element 47, is relatively slideable thereon and also is slideably mounted on the door 7. The slideable mounting on the door 7 is accomplished by means of a slide member 55 slideable in a guide 57 on said door 7. A cover plate 59 holds and prevents the slide 55 from coming out of the guide 57. It will be apparent from the drawing that the slide 55 is fastened rigidly to the member 53, a space 61 being left therebetween for permitting the element 53 to slide up and down. The motion of the terminal-engaging element 53 is limited by the contact of opposite ends of the metal around space 61 with the holding plate 59.

The element 53 also carries oppositely disposed gudgeons 63 which cooperate with spring clips 65 attached to a lower line terminal 67. A line wire 69 completes the circuit.

In order to prevent the insulating telescoping tube 43 from turning with respect to the terminal-engaging element 53 in which it slides, a pin 71 in the element 53 cooperates slideably with a groove 73 in the tube 43. Contact between the upper end of the groove 73 and the pin 71 also limits the downward movement of the tube 43 with respect to the terminal-engaging element 53. The downward movement of the tube 43 is greater than that of the element 53.

The fuse link 51 has the upper conducting element 21, a fusible element 75 therebelow but near the upper terminal-engaging element 13, and a lower conducting element 77 which passes downwardly and out of the open ends 39 and 45 of the tubes 15 and 43, where the link is given a hairpin turn and led upwardly to be fastened at the clamp 49.

Below the terminal-engaging element 13, the box 1 is provided with one element 35 of a septum, the other elements 37 of which is carried by the door 7. These elements 35 and 37, together, form a complete septum which prevents arcing between the upper terminal-engaging element 13 and the lower terminal-engaging element 53.

The operation of the device is as follows:

Assuming the door 7 to have been opened and removed from the box 1, the cap 19 is unscrewed from the upper, fixed, terminal-engaging element 13. The fuse link is then fed through the opening 17, until a head portion on the upper conducting portion 21 is adapted to be clamped by applying the screw 19. The lower conducting element 77 then is extending out of the lower ends of the tubes 15 and 43, while the fusible section 75 is far up in the tube 15.

Next, the tube 43 is pushed up from the position shown in Fig. 2 into the position shown in Fig. 1. In doing this, the terminal-engaging element 53 is contacted by the contact 47 and pushed to its Fig. 1 position on the door. The lower, conducting portion 77 of the link 51 is then given a hairpin turn and led up to the clamp 49 where it is fastened. Then, upon applying the eye 5 of the door 7 to the pin 3, and rotating the door shut, the parts will be positioned as shown in Fig. 1. It is to be understood that after the link is fastened at 21, the mere threading of it through the clamp 49 and drawing it tight, will bring to-

gether the contact 47 and element 53 by sliding the tube 43 in on the tube 15.

The gudgeons 63 and clamp plug 19 are springingly held in the spring clips 25 and 31 respectively, and the gudgeons 63 are springingly pressed down by the spring clips 65. It will be understood that inasmuch as the clips 25, 31 and 65 are conducting, that current is then available to pass through the fuse link. The downward tensioning effect of the upper clips 25, 31 serve to hold the door 7 snugly. The downward tension of the lower clips 65 on the gudgeons 63 causes a tendency to move down the slideable conducting elements 53 against the conducting elements 47. The conducting element 47, being fastened to the slideable insulating tube 43 cannot move downwardly, because the tube 43 rests by gravity on the hairpin turn of the fuse link. Hence, not only does the contact between the spring 65 and gudgeon 63 result in a good current-carrying contact between members 53 and 47, but it also causes the fuse link to be put under some tension. This tension is augmented by the gravity effect of the combined weights of the members 43, 47 and 53.

Upon an overload, the fusible section 75 fuses. This may be accompanied by a violent expansion of gas, as upon a heavy overload, or not, as in the case of a dragging overload. In either event, the slideable terminal-engaging element 53 will be forced downwardly, first by the combined action of gravity and the spring clip 65, and finally by gravity only, from the position shown in Fig. 1 to that shown in Fig. 2. The descent is by reason of the fact that the supporting action of the fuse link no longer is present under the tube 43. Consequently, the tube 43 can descend from the Fig. 1 position to that shown in Fig. 2 and this takes away the support of the member 47 from the member 53. The descent of the member 53 is limited and arrested by contact of the upper end of the slot 61 with the plate 59 (Fig. 2); whereas, the descent of the tube 43 continues but is ultimately limited by contact between the upper end of the groove 73 with the pin 71. A fixed septum 74 at the bottom of box 1 prevents ionized gases from finding ready access back into the box.

The effect of the above action is several-fold. In the first place, the fuse link is suitably tensioned in the circuit by the springs 65, so that upon melting of the fusible element 75, there is an immediate tendency to separate the adjacent conducting elements 21 and 77. However, the springs 25 and 31 add no tension on the fuse link. The force of these springs is carried by the pin 3 of the door hinge. This is advantageous because by this means enough but not too much tension is obtained. The sliding action under springs 65 is easy, whereas that under springs 25 and 31 must be more harsh in order to hold shut the door. This harsh action might break the link if applied thereto.

In the second place, the telescopic elongation of the effective fuse tube, by reason of the dropping of tube 43, causes a quick withdrawal of the conducting element 77 from the fuse cartridge, as indicated in Fig. 2. Otherwise stated, the descent of the tube 43 effects drawing out of the link.

In the third place, the fuse link 51 fastens to the element 47 only and when this element 47 electrically disconnects from the element 63, there is no longer any electrical connection between the fuse link and the line wire 69. Thus the descending link is electrically dead and

harmless, both to the operator and in respect to surrounding objects. Heretofore, the depending link has been undesirably electrically alive. This is true whether or not the clips 65 do not follow 5 the gudgeons 63 for the whole stroke of the gudgeons or whether they do as in Fig. 2.

It will also be seen from Fig. 2 that the projecting end of the tubular element 43 forms a sure, 10 visible indicator of the blown condition of the fuse.

From the position of Fig. 2, the door 7 may be 15 removed from the box 1 and the device re-fused as above described.

In view of the above, it will be seen that the 15 several objects of the invention are achieved and other advantageous results attained.

As many changes could be made in carrying out 20 the above constructions without departing from the scope of the invention, it is intended that all 20 matter contained in the above description or shown in the accompanying drawing shall be interpreted as illustrative and not in a limiting sense.

I claim:

25 1. In apparatus of the class described, two groups of line terminals, a terminal-engaging element for one group of line terminals, a terminal-engaging element for the other group of line terminals, an extension from the first terminal-engaging element, said second terminal-engaging element being movable with respect to the extension, a contact movable with respect to the second terminal-engaging element and separable therefrom, and a fuse link joining the first-named terminal-engaging element with the contact and adapted normally to hold together the second terminal-engaging element and the contact.

2. In apparatus of the class described, spaced 40 line terminals, a fuse support, a terminal-engaging element on said support and cooperating with one line terminal, another terminal-engaging element movable on the support and a contact movable with respect thereto, a fuse 45 fastening means on the contact, a fuse link passing from the first engaging element through said second engaging element and through and to the contact, the second engaging element and contact being movable and held in engagement by the unfused link and being separable when the link fuses.

3. In apparatus of the class described, spaced 55 line terminals, a fuse support, a terminal-engaging element on said support and cooperating with one line terminal, another terminal-engaging element movable on the support and a contact movable with respect thereto, a fuse fastening means on the contact, a fuse link passing from the first engaging element through said second engaging element and through and to the contact, the second engaging element and contact being movable and held in engagement by the unfused link and being separable when the link fuses, the line terminal which engages the second engaging element being adapted to force said element 65 against the contact to tension the link.

4. A fuse comprising a fuse tube, a terminal element at one end of said tube, said tube being open at the other end, a second slidable tube on 70 said first tube, said second tube having an open end normally adjacent the open end of the first tube, a fuse contact on said slidable tube, a fuse joining said last-named contact and said terminal element, and a second terminal element slidable 75 on said slidable tube adapted to be engaged by

said contact when the link is in connected position.

5. In a fuse, a fixed fuse tube, a terminal element at one end of said tube, said tube being open at the other end, a second slidable tube on said first tube adjacent the open end, said second tube having an open end normally adjacent the open end of the first tube, a second terminal element slidable with respect to said slidable tube, a contact on the slidable tube lying outside the two terminal elements, and a fuse adapted to be fastened by the terminal element and to extend through the fixed tube and to hold the slidable tube to force the contact against the second terminal element and to bias the latter toward the first terminal element. 10

6. In a fuse, a fixed fuse tube, a terminal element at one end of said tube, said tube being open at the other end, a second slidable tube on said first tube adjacent the open end, said second tube having an open end normally adjacent the open end of the first tube, a second terminal element slidable with respect to said slidable tube, a contact on the slidable tube lying outside the two terminal elements, and a fuse adapted to be fastened by the first-named terminal element and to extend through the fixed tube and to hold the slidable tube to force the contact against the second terminal element to bias the latter toward the first terminal element and means for tensioning the second terminal element against said contact. 15

7. In apparatus of the class described, a box, a door on said box, upper and lower line terminals in said box, a terminal-engaging element on said door for contacting said upper line terminal, an insulating tube extending from said upper terminal-engaging element downwardly past the lower line terminal, a second insulated tube telescoping the first tube, a contact on said second tube adapted to fasten a fuse link, a link joining said last-named contact and the terminal-engaging element, and a terminal-engaging element movable on said door and adapted to be engaged by said contact when the contact is moved toward the upper terminal-engaging element. 20

8. In apparatus of the class described, a box, a door on said box, upper and lower line terminals in said box, a terminal-engaging element on said door for said upper line terminal, an insulating tube extending from said upper terminal-engaging element downwardly past the lower line terminal, a second insulated tube telescoping the first tube, a contact on said second tube adapted to fasten a fuse link, a link joining said last-named contact and the terminal-engaging element, and a terminal-engaging element movable on said door and adapted to be engaged by said contact when the contact is moved toward the upper terminal-engaging element, said link in normal position holding said contact and lower terminal element toward the upper terminal element. 25

9. In apparatus of the class described, a box, a door on said box, upper and lower line terminals in said box, a terminal-engaging element on said door for said upper line terminals, an insulating tube extending from said upper terminal-engaging element downwardly past the lower line terminal, a second insulated tube telescoping the first tube, a contact on said second tube adapted to fasten a fuse link, a link joining said last-named contact and the terminal-engaging element, and a terminal-engaging element movable on said door and adapted to be engaged by said contact when the contact is 30

- 5 moved toward the upper terminal-engaging element, said link in normal position holding said contact and lower terminal element biased toward the upper terminal element, said lower line terminal resiliently biasing the lower terminal element away from the upper terminal element when said terminal elements contact their respective line terminals.
- 10 10. In apparatus of the class described, a box, a door on said box, upper and lower line terminals in said box, a terminal-engaging element on said door for said upper line terminals, an insulating tube extending from said upper terminal-engaging element downwardly past the lower line terminal, a second insulated tube telescoping the first tube, a contact on said second tube adapted to fasten a fuse link, a link joining said last-named contact and the first-named terminal-engaging element, and a terminal-engaging element movable on said door and adapted to be engaged by said contact when the contact is moved toward the upper terminal-engaging element, said lower terminal-engaging element being thereby moved to such a position that when it engages the lower line terminals, said lower line terminals are tensioned to force the lower terminal-engaging element against said contact to effect electrical engagement with and tensioning of said link.
- 15 11. In apparatus of the class described, a box, a door on said box, upper and lower line terminals in said box, a terminal-engaging element on said door for said upper line terminals, an insulating tube extending from said upper terminal-engaging element downwardly past the lower line contacts, a second insulated tube telescoping the first tube, a contact on said second tube adapted to fasten a fuse link, a link joining said last-named contact and the first-named terminal-engaging element, and a terminal-engaging element movable on said door and adapted to be engaged by said contact when the contact is moved toward the upper terminal-engaging element, said lower terminal-engaging element being thereby moved to such a position that when it engages the lower line terminals, said lower line terminals are tensioned to force the lower terminal-engaging element against said contact to effect electrical engagement and tensioning of said link, the movement of the lower terminal-engaging element with respect to the door being limited to be less than the movement of the second tube and contact with respect to the lower terminal-engaging element.
- 20 12. In apparatus of the class described, spaced, resilient line terminals, a relatively fixed terminal-engaging element contacting one line terminal, a relatively movable terminal-engaging element contacting the other line terminal, an extension from the relatively fixed terminal-engaging element supporting the movable terminal-engaging element for limited movement, a movable fuse contact supported for movement into and out of electrical engagement with the movable terminal-engaging element, and a link joining the fixed terminal-engaging element and said movable contact which in normal position forces said contact against the movable terminal-engaging element to move the latter to resiliently engage the resilient line terminal.
- 25 13. In apparatus of the class described, line terminals, at least one of which is resilient, a fuse comprising a rigid support, a relatively fixed terminal-engaging element for one set of line terminals, a relatively rigid insulating tube ex-
- 5 tending from said fixed terminal-engaging element, a movable terminal-engaging element having limited motion on said support and surrounding said tube, an insulating tube slidable on said rigid tube and between it and the movable terminal-engaging element, and a fuse contact on said slidable tube adapted to engage said movable terminal-engaging element to force the same to assume a springing contact with the resilient line terminal, means for fastening a fuse link 10 to said contact and to the fixed terminal-engaging element, said contact when the fuse link separates being movable with and away from said movable terminal-engaging element.
- 10 14. In apparatus of the class described, a box, a door on said box, a relatively fixed terminal-engaging element attached to said door engageable with one set of line terminals, a relatively movable terminal-engaging element on said door movable 20 to a position of springing engagement with the other set of line terminals, a tubular insulating member movable with respect to said movable terminal-engaging element to a greater degree than said movable terminal-engaging element 25 moves on the door, a contact on said tube, a fixed tube extending from said fixed terminal-engaging element and into said slidable tube and through said movable terminal-engaging element, and a fuse joining said contact and said 30 fixed terminal-engaging element adapted in connecting position to force the contact against the movable terminal-engaging element whereby the tension of the line terminal tensions said link through force applied by the line terminal to the 35 movable terminal-engaging element and the contact, said contact being movable away from the movable terminal-engaging element when the link separates.
- 15 15. A fuse comprising an insulating tube, a fixed terminal-engaging element enclosing one end of said tube, a movable terminal-engaging element at the other end of the tube, a telescoping and insulating tube associated with the fixed insulating tube, and a contact on said 40 telescoping tube engageable with said movable terminal-engaging element.
- 20 16. A fuse comprising an insulating tube, a fixed terminal-engaging element enclosing one end of said tube, a movable terminal-engaging element at the other end of the tube, a telescoping and insulating tube associated with the fixed insulating tube, a contact on said telescoping tube engageable with said movable terminal-engaging element, both of said tubes having 45 normally adjacent open ends, and a fuse link electrically joining the fixed terminal-engaging element with said contact.
- 25 17. A fuse comprising an insulating tube, a fixed terminal-engaging element enclosing one end of said tube, a movable terminal-engaging element at the other end of the tube, a telescoping and insulating tube associated with the fixed insulating tube, a contact on said telescoping tube engageable with said movable terminal-engaging element, both of said tubes having 50 normally adjacent open ends, and a fuse link electrically joining the fixed terminal-engaging element with said contact and normally passing through both tubes and about their open ends.
- 30 18. A fuse comprising an insulating tube, a fixed terminal-engaging element enclosing one end of said tube, a movable terminal-engaging element at the other end of the tube, a telescoping and insulating tube associated with the 55
- 35
- 40
- 45
- 50
- 55
- 60
- 65
- 70
- 75

- fixed insulating tube, a contact on said telescoping tube engageable with said movable terminal-engaging element, both of said tubes having normally adjacent open ends, a fuse link electrically joining the fixed terminal-engaging element with said contact, and a support comprising means fixedly attached to the fixed terminal-engaging element and to which said movable terminal-engaging element is slidably attached.
19. A fuse comprising a tube, a relatively fixed terminal-engaging element thereon, a relatively movable terminal-engaging element thereon, a telescoping member, a contact on said telescoping member, a link joining said fixed terminal-engaging element and said contact and adapted to hold the telescoping member in such a position that the contact and the movable terminal-engaging element are normally in electrical contact, said contact and movable terminal-engaging element being separated by the sliding action of said movable terminal-engaging element upon parting of the link.
20. A fuse comprising a tube, a relatively fixed terminal-engaging element thereon, a relatively movable terminal-engaging element thereon, a telescoping member, a contact on said telescoping member, a link joining said fixed terminal-engaging element and said contact and adapted to hold the telescoping member in such a position that the contact and the movable terminal-engaging element are normally in electrical contact, said contact and movable terminal-engaging element being separated by the sliding action of said movable terminal-engaging element upon breaking of the link, said link in unbroken condition normally supporting said telescoping member but in broken condition releasing the same to withdraw a substantial portion of the link from the tube.
21. A fuse comprising a tube, a relatively fixed terminal-engaging element thereon, a relatively movable terminal-engaging element thereon, a telescoping member, a contact on said telescoping member, a link joining said fixed terminal-engaging element and said contact and passing through the tube and adapted to hold the telescoping member in such a position that the contact and the movable terminal-engaging element are normally in electrical contact and biased toward the fixed element, said contact and movable terminal-engaging element being separated by the sliding action of said movable terminal-engaging element upon the parting of the link.
22. A fuse comprising a rigid member, a relatively fixed terminal-engaging element thereon, a relatively movable terminal-engaging element thereon, a slidible member on the rigid member, a contact on said slidible member, a link joining said fixed terminal-engaging element and said contact and adapted to hold the slidible member in such a position that the contact and the movable terminal-engaging element are normally in electrical contact, said contact and movable terminal-engaging element being separated by the sliding action of said slidible member upon the parting of the link.
23. A fuse comprising a rigid member, a relatively fixed terminal-engaging element thereon, a relatively movable terminal-engaging element thereon, a slidible member on the rigid member, a contact on said slidible member, a link joining said fixed terminal-engaging element and said contact and adapted to hold the slidible member in such a position that the contact and the movable terminal-engaging element are normally in electrical contact, said contact and movable terminal-engaging element being separated by the sliding action of said slidible member upon the parting of the link.
24. In apparatus of the class described, an enclosing box having an open lower end, upper and lower springing line terminals in said box, a door on the box, a relatively fixed terminal-engaging element attached to said door engageable with the upper set of line terminals, a lower relatively movable terminal-engaging element on said door movable to a position of springing engagement with the lower set of line terminals, a tubular insulating member downwardly movable with respect to said movable terminal-engaging element to a greater degree than the downward movement of said movable terminal-engaging element on the door, a contact on said tube, a fixed tube extending from the fixed terminal-engaging element and surrounded by said slidible tube and extending through said movable terminal-engaging element, and a fuse joining said contact and said fixed terminal-engaging element adapted in connected position to bias the contact and the movable terminal-engaging element toward the fixed terminal-engaging element, whereby upon closure of the door the lower line terminal is tensioned to react to tension the link and improve the electrical contact between the contact and lower terminal-engaging element.
25. In apparatus of the class described, an enclosing box having an open lower end, upper and lower springing line terminals in said box, a door on the box, a relatively fixed terminal-engaging element attached to said door engageable with the upper set of line terminals, a lower relatively movable terminal-engaging element on said door movable to a position of springing engagement with the lower set of line terminals, a tubular insulating member downwardly movable with respect to said movable terminal-engaging element to a greater degree than the downward movement of said movable terminal-engaging element on the door, a contact on said tube, a fixed tube extending from the fixed terminal-engaging element and surrounded by said slidible tube and extending through said movable terminal-engaging element, and a fuse joining said contact and said fixed terminal-engaging element adapted in connected position to bias the contact and the movable terminal-engaging element toward the fixed terminal-engaging element whereby upon closure of the door the lower line terminal is tensioned to react to tension the link and improve the electrical contact between the contact and lower terminal-engaging element and whereby upon separation of the link the contact falls away from the lower terminal-engaging element said movable tube telescoping out from the fixed tube to withdraw the remainder of the link therefrom and give visible indication that the fuse link has parted.
26. In apparatus of the class described, line terminals, a terminal-engaging element permanently engageable with one line terminal without movement after manual engagement and until manual disengagement, a terminal-engaging means for the other line terminal, an extension from the terminal-engaging element, said terminal-engaging means being movable with respect to the extension, and a fuse link joining said terminal-engaging element and the terminal-en-

- gaging means adapted normally to hold said terminal-engaging means in a position against its respective line terminal, but when fused, to permit movement of said terminal-engaging means away from said respective line terminal to draw the link away from said terminal-engaging element without movement of said terminal-engaging element. 5
27. In apparatus of the class described, line terminals, a terminal-engaging element permanently engageable with one line terminal without movement after manual engagement and until manual disengagement, terminal-engaging means for the other line terminal, said terminal-engaging means having at least one part movable to electrically disconnect from the respective line terminal, and a fuse joining said part with the other terminal-engaging element, said fuse when connected and unfused normally holding said 10 terminal-engaging means in electrical connection with its respective terminal-engaging element but when fused to electrically separate these without movement of said terminal-engaging element. 15
28. In apparatus of the class described, a box, line terminals in the box, a terminal-engaging element permanently engageable with one line terminal, terminal-engaging means for the other line terminal without movement after manual engagement and until manual disengagement, a fuse tube extending from the terminal-engaging element, the terminal-engaging means having at least one part movable with respect to said tube away from the said terminal-engaging element, a fuse link connecting said movable part and said terminal-engaging element adapted normally to bias the terminal-engaging means toward the terminal-engaging element, and when fused to permit the terminal-engaging means to move from the terminal-engaging element to draw said link from said tube without movement of said terminal-engaging element, and a manually operable door hinged to the box and carrying said terminal-engaging element to effect said 45 manual operation thereof. 40
29. In apparatus of the class described, a box, spaced line terminals therein, one of which terminals has a bias, a door hinged to the box, a fuse tube on the floor, terminal-engaging elements on 50 said tube cooperable with said line terminals, at least one of said terminal-engaging elements being movable with respect to the tube, and a fuse link joining with said movable terminal-engaging element, means for rigidly holding said link at 55 its other end to bias said movable terminal-engaging element against the line terminal having the bias, whereby upon blowing of the link, said movable terminal-engaging element is biased to draw the link from the tube without movement of 60 said door. 55
30. In apparatus of the class described, a base, spaced line terminals thereon, one of said terminals having a bias away from the other, a hinged member on the base, terminal-engaging elements on the hinged member cooperable with said line terminals, at least one of said terminal-engaging elements being movable with respect to the hinged member, a fuse link joining with said movable terminal-engaging element, means for rigidly holding said link at its other end to the other terminal-engaging element to bias said movable terminal-engaging element against the biased line terminal in a predetermined position of the hinged member, whereby upon blowing of the link said movable terminal-engaging element is biased by the biased line terminal to draw the link without movement of said hinged member from said 10 predetermined position. 15
31. In apparatus of the class described, a base, spaced line terminals thereon, a hinged member on the base, terminal-engaging elements on the hinged member cooperable with said line terminals, at least one of said terminal-engaging elements being movable with respect to the hinged member, a fuse link joining with said movable terminal-engaging element, means for rigidly holding said link at its other end to the other terminal-engaging element to bias said movable terminal-engaging element into contact against the other line terminal, said contact being resilient, whereby upon blowing of the link said movable terminal-engaging element is movable 20 from its line terminal to draw the link without movement of said hinged member. 30
32. In apparatus of the class described, a base, at least one line terminal thereon, a hinged member on the base, at least one terminal-engaging element on the hinged member which is movable and cooperable with said line terminal, a fuse link joining said movable terminal-engaging element, means for holding said link at its other end to hold said movable terminal-engaging element against said line terminal in a predetermined position of the hinged member, and means whereby upon blowing of the link said movable terminal-engaging element is released without movement of said hinged member from 40 45
33. In apparatus of the class described, a box, a hinged door on the box movable into closed position, at least one line terminal in the box, at least one terminal-engaging element relatively 50 movable on and movable with the door and cooperable with said line terminal when the door is closed, a fuse link joining said terminal-engaging element, means for anchoring said link in its other end with respect to the door to force said movable engaging element against said line terminal when the door is closed, and means whereby upon blowing of the link said movable terminal-engaging element is released without movement of said door from closed position. 55 60

THEODORE BIRKENMAIER.

CERTIFICATE OF CORRECTION.

Patent No. 2,077,207.

April 13, 1937.

THEODORE BIRKENMAIER.

It is hereby certified that error appears in the printed specification of the above numbered patent requiring correction as follows: Page 6, first column, line 49, claim 29, for "floor" read door; and that the said Letters Patent should be read with this correction therein that the same may conform to the record of the case in the Patent Office.

Signed and sealed this 29th day of June, A. D. 1937.

Henry Van Arsdale

(Seal)

Acting Commissioner of Patents
